Giuseppe Garella, Turin, Piedmont, Italy

Filed Apr. 26, 1965, Ser. No. 84,953

Term of patent 7 years

(Cl. D34—2)

Fig. 1

FIG. 1 is a side elevational view of a toy animal figure showing my new design; and

FIG. 2 is a front elevational view thereof.

The characteristic feature of my design resides in a toy animal figure in the form of a chicken having as a hat half of an eggshell, all as shown.

I claim:

The ornamental design for a toy animal figure, as shown and described.
